GAP CONNECTOR IN IGNITION
GENERATORS

Wolfgang E. Schwarzmamn, Longmeadow, Mass.,
assignor to American Bosch Corporation,
Springfield, Mass., a corporation of New York

Application May 9, 1940, Serial No. 334,162

8 Claims. (Cl. 171—209)

The present invention relates to gap connectors with axially telescoped electrodes of which one is stationary and the other is rotatable with an annular gap between them, said electrodes being electrically connected between the high tension terminal of a stationary ignition coil and the distributor rotor or for multicylinder ignition generators, such as magnetos and timers, for the purpose of conducting the intermittent impulses of high tension ignition currents to the distributor for sequential distribution thereof to high tension sparkplugs of an associated internal combustion engine.

Heretofore a carbon brush was used to electrically connect the ignition coil to the distributor rotor, but trouble developed, particularly in aviation magnetos and timers operating under severe vibration, due to many causes such as the wear and breakage of the brush, the deposition of carbon particles and smear from the brush, pitting and corrosion resulting from sparking and arcing, and the breakage of the brush spring due to crystallization. When the spring pressure was increased in an endeavor to prevent arcing, the brush wear increased, and the arcing increased when the spring pressure was decreased. Brushes of metal and springs of different forms to obviate some of these troubles have performed unsatisfactorily. In service, these troubles led to the requirement for frequent repair and replacement which sometimes introduced dangers in flight when used on airplanes. On the other hand, if a gap connector of ordinary form is used in the circuit between the ignition coil and the distributor rotor, the impedance of this gap plus that of the air gap between the rotor and each of the stationary electrodes of the distributor to which the sparkplug cables are connected, may result in such high total spark energy loss that under some conditions the effectiveness of the ignition sparks at the spark plugs is reduced and likewise the power output and dependability of the engine.

In accordance with one part of my invention, a gap connector with a comparatively large value of electrical capacitance or comparatively low value of impedance is provided in the circuit between the stationary high tension ignition coil and the rotary electrode of a jump spark distributor to conduct the current impulses for distribution to the sparkplug cables. In accordance with another part of my invention, whether a jump spark or a brush type distributor is used, and whether the distributor is incorporated in the magneto or timer or separated therefrom, the

gap connector comprises two electrodes of which one is recessed closely and compactly within the other to conduct the current impulses through an air gap therebetween which has a large surface area and a comparatively small length or radial depth. The two electrodes of the gap are thus telescoped to form a gap of generally annular form, having in some cases if desired an additional end or disc gap, whereby not only is the surface area between the electrodes increased considerably in comparison with gaps of the well known form in jump spark distributors but a partially enclosed space is formed between the relatively rotatable electrodes which confines the heated gases therebetween and thus enhances and stabilizes the ionized condition of those gases which further reduce the drop in voltage through the gap connector. In this way, not only is the ignition increased in effectiveness and reliability, resulting in improved overall engine output and dependability, but the gap connector outlasts many of the other parts of the magneto or timer due to the marked reduction in pitting, corrosion and erosion of the electrodes. These and other advantages, such as compactness, cheapness and ease of assembly and disassembly, will be apparent from the following description taken in connection with the accompanying drawing, illustrating several embodiments of my invention as applied, as examples, to magnetos having jump spark distributors incorporated therein and to magnetos or timers associated with independently driven distributors. In the drawing,

Fig. 1 shows in central elevational section a magneto with the high tension terminal of its stationary ignition coil in the form of a cup electrode into which extends a rod electrode fastened to the distributor rotor on the axis of rotation thereof to form a gap connector therewith; Fig. 2 is an enlarged section on line 2—2 of Fig. 1; Fig. 3 is a modified form of gap connector in which the outer electrode is in the form of a ring carried by the coil terminal; and Fig. 4 shows a separate distributor in which the gap connection is formed by a cup electrode fastened on the axis of the distributor rotor and a pin electrode projecting into the cup from a bracket electrically connected to a cable from the ignition coil of the generating element of the ignition source.

Referring to the embodiment of Figs. 1 and 2, the numeral 1 generally designates a magneto having a generating rotor 2 and a stator structure 3, of any suitable kind, with a stationary ignition coil 4 having primary and secondary windings of well known kind. The live end of

the secondary or high tension winding is connected to a terminal 5 of a suitable nickel alloy fastened rigidly in position on the coil by a rivet or soldering at 6 and having a cylindrical cavity or recess at 7 forming a cup-shaped member. The generating rotor 2 carries a pinion 8 meshed with a distributor gear 9 of suitable ratio mounted for rotation in the ball bearing 10. To the gear is fastened by screws 11 the distributor rotor 12 of insulating material. Molded in this rotor is a distributor arm or electrode 13 riveted or otherwise fastened along its axis of rotation to a generally cylindrical pin or rod 14 of a suitable nickel alloy which projects centrally into the recess 7. The cylindrical collar 15 serves to anchor the pin in the molding and the annular projection 16 of the molding electrically shrouds the gap connector against flashover to the metal parts of the magneto. The outwardly projecting part 17 of the electrode 13 registers sequentially with the stationary distributor electrodes 18 of the magneto, which terminals are mounted in the distributor plate 19 of insulating material and are fastened electrically by piercing screws 20 to the sparkplug cables 21. The stationary member 22 of insulating material forms an apron under the distributor rotor to prevent flashover from the projecting portion 17 to metal parts of the magneto.

The modified gap connector of Fig. 3 has the axially rotatable metal pin or rod 23 fixed in a rod 24 extending from the distributor rotor electrode (not shown) which pin or rod projects into the metal ring 25. This ring is adjustably suspended from the terminal 26 of the stationary ignition coil 4 by a metal arm 27 which may be bent or adjusted to give an annular gap between the electrodes 23 and 25 of substantially uniform depth. As before, the shroud 28 is of insulating material and integral with the rotor of the distributor which may be of the brush or jump spark type.

In the embodiment of Fig. 4, the rotor 29 of the distributor, which is disassociated from the generating element of the magneto, timer or other ignition source, is driven by the engine through gearing of the proper ratio (not shown). In this case it is the electrode 30, fastened to the arm 31 on the axis of the distributor rotor that is cup-shaped, while the pin or rod electrode 32 projects thereinto to form annular and disc gaps therewith. The gap connector thus formed is protected by the shroud 33 and the electrode 32 is suspended by a bendable arm 34 from a bracket 35 which in effect forms the terminal of the high tension ignition coil by being electrically connected by the piercing screw 36 to the cable 37 that leads from the ignition coil. This arm may be bent or adjusted to give the desired gaps. In this embodiment, a jump spark distributor is shown but it may be replaced by one of the brush type in ways that will be obvious.

It will be observed that the annular air gaps of the gap connector of all embodiments herein described, particularly when supplemented by the additional disc gaps of Figs. 1 and 4, have a cross sectional area so much greater, on account of the telescoped electrodes, than that between the electrodes of a jump spark distributor, and can have a length or radial depth so much less, on account of the small diameter of the gap and the mounting of the rotatable electrode thereof at the axis of the distributor rotor instead at a place removed therefrom, that the current carrying capacity of these gap connectors between the

ignition coil and the distributor is considerably greater, and the impedance thereof considerably less, than that of any of the gaps of the jump spark distributor. In fact, the annular gap can have almost no depth by initially providing little or substantially no tolerance between the electrodes thereof. The result is that the loss in sparking voltage in this type of gap connector between the ignition coil and the distributor is so small that the characteristics of the ignition spark at the sparkplugs in the engine cylinder are not affected to any noticeable extent. At the same time the troubles above noted in a brush connector between the coil and distributor are obviated. Also, the surfaces in registration between the members of these forms of gap connectors are so extended on account of being telescoped, and the annular gaps can be maintained so uniformly in depth on account of their small diameter, that the sparking between the gap electrodes is divided at each period of ignition or readily shifts to different places at different periods of ignition, which thereby reduces the pitting and erosion over the electrodes to such an extent that the gap connector functions satisfactorily over longer periods of operation than do gap connectors of prior constructions. Furthermore, the sparking zones of these gap connectors are so restricted or partially confined from ventilating air currents, particularly on account of the insulating shroud around them, that the air or gases between the telescoped electrodes quickly becomes stabilized in an ionized condition which further decreases the impedance of the gap connector. The ionized and corrosive gases in this gap connector being partially confined in the annular gap are not so readily diffused with the surrounding air and, therefore, do not become harmful to the other parts of the ignition apparatus. If desired, the ventilating passages 38 may be provided in any of the gap connectors in the event that either electrode thereof gets too hot in operation.

It is obvious that other modifications of my gap connectors and their incorporation in magnetos, timers or other ignition generators may be provided within the broad terms of the appended claims and such modifications also are therefore intended to be covered thereby.

Having thus described my invention, what I claim is:

1. In a multicylinder ignition system for high tension sparkplugs of an internal combustion engine, a stationary ignition coil having a high tension terminal, a source of intermittent current supply for said coil, a jump spark distributor having a rotatable electrode and a plurality of stationary electrodes for connection to respective sparkplugs, said rotatable and stationary electrodes registering sequentially with an air gap therebetween, and a gap connector electrically connected between said coil terminal and said rotatable electrode of said distributor and having axially telescoped electrodes of which one is stationary and the other is rotatable with an annular gap between them, the impedance of said gap connector being less than the impedance of any of said distributor gaps.

2. In a multicylinder ignition system for high tension sparkplugs of an internal combustion engine, a stationary ignition coil having a high tension terminal, a source of intermittent current supply for said coil, a distributor having a distributor rotor and a plurality of stationary sparkplug terminals sequentially registerable there-

with, and a gap connector electrically connected between said coil terminal and said distributor rotor and having axially telescoped electrodes of which one is stationary and the other is rotatable with an annular gap between them.

3. In a multicylinder ignition system for high tension sparkplugs of an internal combustion engine, a stationary ignition coil having a high tension terminal, a source of intermittent current supply for said coil, a distributor having a distributor rotor and a plurality of stationary sparkplug terminals sequentially registerable therewith, and a gap connector electrically connected between said coil terminal and said distributor rotor and having axially telescoped electrodes of which one electrode is stationary and the other is rotatable with an annular gap between them and of which one electrode is cup-shaped with a disc gap between its bottom surface and the other electrode.

4. In a multicylinder ignition system for high tension sparkplugs of an internal combustion engine, a stationary ignition coil having a high tension terminal, a source of intermittent current supply for said coil, a distributor having a distributor rotor and a plurality of stationary sparkplug terminals sequentially registerable therewith, and a gap connector electrically connected between said coil terminal and said distributor rotor and having axially telescoped electrodes of which one electrode is stationary and the other is carried by the distributor rotor on the axis of rotation thereof to form an annular gap with the stationary electrode.

5. In a multicylinder ignition system for high tension sparkplugs of an internal combustion engine, a stationary ignition coil having a high tension terminal, a source of intermittent current supply for said coil, a distributor having a distributor rotor and a plurality of stationary sparkplug terminals sequentially registerable therewith, and a gap connector electrically connected between said coil terminal and said distributor rotor and having axially telescoped electrodes of which one is stationary and the other is rotatable with an annular gap between them, one of said

electrodes being adjustable in position to provide adjustment for said annular gap.

6. In a multicylinder ignition system for high tension sparkplugs of an internal combustion engine, a stationary ignition coil having a high tension terminal, a source of intermittent current supply for said coil, a distributor having a distributor rotor and a plurality of stationary sparkplug terminals sequentially registerable therewith, and a rotatable gap connector with axially telescoped electrodes of which one electrode is formed by said coil terminal and the other is carried by the distributor rotor on the axis of rotation thereof to form an annular gap with the said coil terminal.

7. In a multicylinder ignition system for high tension sparkplugs of an internal combustion engine, a stationary ignition coil having a high tension terminal, a source of intermittent current supply for said coil, a distributor having a distributor rotor and a plurality of stationary sparkplug terminals sequentially registerable therewith, and a rotatable gap connector with axially telescoped electrodes of which one electrode is supported from said coil terminal by a bendable conducting support extending therefrom and of which the other electrode is carried by said distributor rotor in electrical connection therewith to form an annular gap with the first named electrode.

8. In a multicylinder ignition system for high tension sparkplugs of an internal combustion engine, a stationary ignition coil having a high tension terminal, a source of intermittent current supply for said coil, a distributor having a distributor rotor and a plurality of stationary sparkplug terminals sequentially registerable therewith, and a gap connector electrically connected between said coil terminal and said distributor rotor and having axially telescoped electrodes of which one electrode is stationary and the other is rotatable with an annular gap between them, the outer one of said telescoped electrodes having a ventilating passage through it.
